UNITED STATES PATENT OFFICE.

PERLE GIBSON SEMPLE OF STAMFORD, CONNECTICUT.

BED-COVERING AND THE LIKE.

1,291,191.

Specification of Letters Patent. Patented Jan. 14, 1919.

Application filed December 17, 1917. Serial No. 207,529.

To all whom it may concern:

Be it known that I, PERLE GIBSON SEMPLE, a citizen of the United States, residing at Stamford, in the county of Fairfield and State of Connecticut, have invented certain new and useful Improvements in Bed-Coverings and the like, of which the following is a specification, reference being had therein to the accompanying drawing.

10 This invention relates to improvements in bed coverings, and more particularly to blankets and the like for babies' cribs or carriages.

15 The invention has for its object the provision of an article of the character stated, so formed that in use, it will be impossible for an infant to kick-off its covering, to expose its hands to the cold or to suck its thumb.

20 The invention also embraces the provision of a covering having improved means enabling easy attachment thereof about the neck of the infant; and also provided with a bib portion,—conveniently a separate element,—25 to protect the covering portion in a manner readily understood.

As a part of this specification I have illustrated the preferred embodiment of the invention, and an inspection of such illustration in connection with the specific description hereinafter contained, will make clear the features to which I have alluded, and also other features in detail and arrangement of parts, all presenting an inexpensive, 30 simple and serviceable article.

In the drawings:

Figure 1 is a front view of the blanket complete.

Fig. 2 is a rear view, and

40 Figs. 3 and 4 are transverse sectional views, the former showing the manner of closing the blanket proper about the neck of the infant, and the latter showing the manner of closing the bib.

45 Referring more specifically to the drawings wherein like reference letters designate the same parts of the several views, A represents the body of a blanket or other bed covering, usually of a suitable material and 50 size for a baby's crib or carriage, although the material is optional, and obviously any size desired may be employed. B is a neck opening formed in the blanket of a size to closely surround the neck of the occupant, 55 access to the neck opening being afforded through a divided portion C in the upper

end of the blanket but offset to one side of the center of the neck opening so that the head of the occupant will not bear thereon, and the divided portion being overlapped as 60 shown and secured by spring-ball fasteners D or equivalent devices with a longer overlapping portion outermost and facing toward the adjacent edge of the blanket to prevent cold air possibly reaching the under side 65 of the blanket from gaining access to the head or neck of the user.

E is a bib of light, soft, washable material provided with a neck opening F adapted to register with the neck opening in the 70 blanket. The bib is conveniently of rectangular outline and provided with diagonally disposed button holes G adapted to detachably receive buttons H suitably positioned and secured on the face of the blanket 75 A. Those portions of the bib overlying the upper divided portion of the blanket and adapted to underlie the back and sides of the head of the user are continuous whereas the lower central portion of the bib is divided as 80 represented at J to enable the bib to be readily slipped around the neck and to be then secured in place through the medium of an intermediate button K also fastened on the face of the blanket and engaged by crossed, 85 inclined, button holes L in the overlapping edges of the divided portion of the bib, the crossed or intersecting button holes tending to more adequately maintain the closed or button and button hole engagement of the 90 bib when in use. Above the engagement just defined, that is at the inner edges of the overlapped portions of the bib and at the marginal corners of the neck-receiving portion, are furnished a pair of short tapes or flexible 95 tie members M adapted to be drawn together and tied to secure the bib about the neck of the infant, these tie members affording means for adjusting the size of the neck opening within reasonable limits.

100 While I have herein disclosed a special embodiment of the invention, it will be apparent to persons skilled in the art to which the invention relates that the invention is capable of embodiment in other forms of devices as may be comprehended by the hereto appended claims.

105 What I claim is:—

1. A bed covering of the character described provided with a neck opening and 110 a detachable integral bib completely surrounding said neck opening to constitute a

protector adapted to underlie the head and in part to overlie the body below the head, the covering and body of the bib having divided portions permitting the placing thereof around the neck of the user whereby portions of both the covering and bib may underlie the head of the user.

2. A bed covering of the character described provided with a neck opening and a detachable bib surrounding said neck opening, the covering and bib having divided portions permitting the placing thereof around the neck of the user whereby portions of the covering and bib may underlie the head of the user, the said divided portions of the covering and bib being arranged at different points relative to each other.

3. A bed covering of the character described provided with a neck opening and a detachable bib surrounding said neck opening, the covering and bib having divided portions permitting the placing thereof around the neck of the user whereby portions of the covering and bib may underlie the head of the user, the said divided portions of the covering and bib being located respectively at the upper portion of the covering and opposite or lower portion of the bib.

4. A bed covering of the character described provided with a neck receiving opening adjacent a part adapted to underlie the head of the user, and having a bib portion adapted to surround the neck of the user, said bib being divided at one edge and furnished with separable fastening means.

5. A bed covering of the character described provided with a neck receiving opening adjacent a part adapted to underlie

the head of the user, and having a bib portion adapted to surround the neck of the user, said bib being divided at one edge and furnished with separable fastening means, said fastening means including an attachment between the bib and the covering, and an attachment between the adjacent adjoining parts of the divided portion of the bib.

6. A bed covering of the character described provided with a neck opening adjoining a portion adapted to underlie the head of the user, and having a bib portion also provided with a neck opening, the bib portion being divided at a point leading to the neck opening, and means for securing the divided parts together.

7. A bed covering of the character described provided with a neck opening adjoining a portion adapted to underlie the head of the user, and having a bib portion also provided with a neck opening, the bib portion being divided at a point leading to the neck opening, and adjustable means for securing the divided parts together and to regulate the size of the neck opening.

8. A bib of the character described provided with a neck opening adjoining a portion adapted to underlie the head of the user and be attached to a blanket or the like, said bib having overlying attaching portions provided with crossed button holes, substantially as described.

In testimony whereof I hereunto affix my signature in the presence of two witnesses.

PERLE GIBSON SEMPLE.
